UNITED STATES PATENT OFFICE.

JOSEPH PETRICEK, OF CHICAGO, ILLINOIS.

NAILING DEVICE.

Application filed June 21, 1922. Serial No. 569,833.

To all whom it may concern:

Be it known that I, JOSEPH PETRICEK, a citizen of Czechoslovakia, residing at Chicago, in the county of Cook and State of Illinois, have invented certain new and useful Improvements in Nailing Devices, of which the following is a specification.

This invention relates to improvements in nailing devices and more particularly to such as are used by cobblers in repairing shoes. The primary object is to provide a hand-operated device that is speedy in operation and practically noiseless. A further object is to provide a device that is positive and efficient in operation and that anyone of ordinary intelligence may readily learn to operate.

With the foregoing and other objects in view the invention consists in the combination and arrangement of parts to be hereinafter fully described, pointed out in the appended claim and illustrated in the accompanying drawing which forms a part of this application and in which—

Fig. 1 is a fragmentary view of the device in front elevation.

Fig. 2 is a view of the device in side elevation, partly in section.

Fig. 3 is an enlarged fragmentary view of the device illustrating the nail magazine and chute.

Fig. 4 is a fragmentary sectional view taken on line 4—4 of Fig. 6.

Fig. 5 is a fragmentary view illustrating the operating lever and connections.

Fig. 6 is a fragmentary view of the device in elevation.

Fig. 7 is a fragmentary sectional view of Fig. 6 with the movable parts in an altered position.

Like reference characters denote corresponding parts throughout the several views:

The device comprises the clamp 1 formed with the jaw extension 2, whereby it may be secured to a work bench, between which members a socket is formed to receive the post 3, a screw-bolt 4 serving to tighten the socket about the post. An adjustable socket 5 is formed at the opposite end of the said bracket 1 to receive the shank of the last 6 that holds the shoe 7 being repaired. A web plate 8 is formed with a tubular extension 9 adapted for adjustable arrangement upon the said post 3, a screw bolt 10 fitted into said extension being adapted for fric-

tional engagement with the post to retain said members in adjusted position.

A magazine 11 formed at its throat with lateral spaced lips 12, 13 is arranged upon one side of the web plate and secured thereto by screws 14 that extend through a plate 15 and through posts 16, 17 upon one side of said plate, into the said web. The plate 15 is an extension of the lip 12 and merges into the chute 18, at the base thereof, that communicates with the magazine, the throat 19 of which is in alignment with the space between the lips 12, 13. The chute 18 has the portions 20, 21 of its sides pressed inwardly, as clearly shown in Fig. 4, thus forming a raceway for the nails 22, the side portion 20 being spaced away from the top 23 of the chute to permit observation of the travelling nail's and access thereto should the raceway become clogged.

In the portions 20, 21 of the sides of the chute the flat springs 24, 25 are secured, the spring 24 having its free end bent inwardly and extending through a perforation 26 in the chute-side into the chute just beyond or above the tread surface of the raceway, the spring 25 having its body portion bent outwardly from the chute-side and its free end bent at an angle to the body portion and disposed in one of a pair of aligned perforations in the chute sides, but upon the opposite side of the tread surface of the raceway with relation to the end of the spring 24, so that pressure upon the bulged portion of the spring 25 will cause the end thereof to pass through both openings in the chute and contact with the spring 24 and press the same outwardly from the chute withdrawing the bent end of the same from the interior thereof and out of the nail-passageway.

A post 27 is carried by the plate 15 and pivotally arranged thereupon is the rocker 28 having the segmental head 29 adapted for oscillation in and out of the throat 19 of the magazine, two extreme positions of said rocker being shown in Figs. 6 and 7, said rocker being formed also with the elongated recessed portion 30 which, in one position of the rocker, contacts with the post 17, the post 16 contacting with the rocker head in the extreme opposite position of the same. A spring 31 wound about the post 27 with one of its ends secured to the rocker has its opposite end in engagement with the post 17 whereby the rocker is

yieldingly retained in raised position in the throat of the magazine and in contact with the post 16.

Upon a pin 32 carried by the rocker the 5 segmental end 33 of the compound lever portion 34 is pivotally arranged, said lever 34 being connected by the slotted link 35 to a pin 36 carried by the lever 37 fulcrumed upon the pin 38 carried by the ear 39 of the 10 recessed head plate 40, said lever 37 being connected also by a link 41 to a pin 42 disposed in an elongated slot 43 in said head plate, said pin carrying the reciprocating hammer 44 arranged in the head plate.

15 Referring again to the lever end 33 the same carries a heel 45 which, as the lever operates, engages with one end of the dog 46 fulcrumed upon a pin 47^a connecting the upturned ears of a casting 48^a, carried by 20 the plate 15, and depresses the opposite end of said dog that rests against the spring 25 and depresses the same thus causing displacement of the spring 24 in a manner previously described. The lever 37, reciprocated by hand, thus at each stroke displaces the rocker-head 29 from the magazine throat and at the same time displaces the yielding spring 24, the springs 31 and 25 returning the rocker, lever and dog 46 to normal position after each of said strokes.

25 The hammer 44 is formed with the recessed portion 47 which, in one position of the hammer, receives the inwardly bent ends 48 of the guide levers 49 fulcrumed in the 30 recessed portion of the head plate upon the pins 50 thus permitting movement of the levers upon their pins. Each lever 49 is formed with a longitudinal recess 51 that merges into a contracted groove 52; and 35 with a lateral recess 53 aligned with the perforation 54 in the head plate that registers with the mouth of the chute 18. A cover plate 55 is provided for the head plate.

40 The magazine 11 is provided with the hinged cover 56 adapted to be retained in closed position by the spring clasp 57. With the cover open the nails are placed in the magazine, the cover then closed and the lever 45 operated. Each time the lever 37 is depressed the rocker is moved into the position shown in Fig. 6 thus permitting the pointed ends of the nails to project into the throat 19 of the magazine. One or more of 45 the nails may gravitate into the chute 18 but

if they should not do so the return of the lever to normal position, through action of the springs previously described, will return the rocker to raised position in the magazine which will impel the nails forward 50 into the chute. The head of the rocker first enters the throat 19 at the most remote point from the chute and rides upward and forward in the throat until it fills the throat thus impelling the nails forward and into 55 the chute. The heads of the nails will ride upon the tread portion of the raceway, the nail bodies extending down between the walls 20, 21 as shown in Fig. 7. Each movement of the operating lever 37 will force 60 the spring 24 out of the path of the nails and permit one nail at a time to drop from the mouth of the chute through the perforation in the head plate and through the recess 53 in the levers 49 into the recesses 51 65 thereof in which position they are directly beneath the end of the hammer which, at its next descent will strike the head of the nail and force it into the shoe. The operator so guides the shoe upon the last that the successive nails will be driven into the parts of the shoe sole or heel desired. Each time the free end of the lever 37 is depressed a nail is driven by the hammer into the shoe and as the lever is returned to normal position another nail is released and positioned beneath the hammer ready for the next stroke.

65 What is claimed is:—

In a nailing device, a work support, a nail magazine, a nail chute registering therewith, 90 a plate connecting said chute and nail magazine, nail-feeding mechanism associated with said plate for feeding the contents of said magazine into said chute, a recessed head plate formed with a perforation in alignment with the mouth of said chute, a reciprocating hammer arranged in the recessed portion of said head plate, twin levers arranged in said head plate and operatively associated with said hammer, said levers being formed with 95 nail-receiving recesses in the plane of said hammer, and lever controlled mechanism for actuating said hammer.

In testimony that I claim the foregoing as my own I have hereto affixed my signature 100 in the presence of two subscribing witnesses.

JOSEPH PETRICEK.
